UNITED STATES PATENT OFFICE.

ARTHUR F. O'CONNOR, OF CHICAGO, ILLINOIS, ASSIGNEE TO UNION RAILWAY EQUIPMENT CO., OF CHICAGO, ILLINOIS, A CORPORATION OF ILLINOIS.

UNCOUPLING DEVICE.

Application filed March 31, 1924. Serial No. 703,094.

This invention relates to devices for operating the locks of couplers used on railway rolling stock and particularly to devices used to connect the coupler pin to a lever system 5 provided to permit operation of the coupler pin from the side of the car or structure to which it is attached.

One of the objects of this invention is to provide a connecting device between the 10 coupler pin and the operating lever system that can be installed or removed without necessitating the removal of any of the parts of the lever system or the dismantling of the coupler parts.

Another object of this invention is to provide a connecting device to operate the coupler pin, having a limited freedom of motion 15 in the direction of its length, and to provide sliding parts of such design and material 20 that excess wear will not occur even with prolonged use.

A further object is to provide a connecting device consisting of separate parts that cannot possibly be assembled in any way 25 other than that intended, that may be forcibly connected without the application of tools, and to provide a device that may be connected and disconnected many times 30 without causing any of its parts to be unfit for further use.

Another object of this invention is to provide a device that will make possible the application and successful use of lever systems 35 provided to allow cars to be coupled and uncoupled from their sides; thus to remove the necessity for the railway employees entering between the cars to couple and uncouple the cars due to inoperative uncoupling devices and the great risk attendant thereto; thus 40 being the cause of a large number of accidents and fatalities among trainmen and also constituting an infraction of the U. S. safety appliance laws.

A further object of this invention is to 45 provide a connecting device of an extensible and movable nature that will withstand continued shock and vibration, and that at the same time cannot possibly be unintentionally freed from its holdings.

Other objects of the invention will appear 50 hereinafter, the novel features and combinations being set forth in the appended claims.

Referring to the accompanying drawings—

Fig. 1 is an elevational view of the connecting device, showing its relation to the lever system and to the coupler pin; 55

Fig. 2 is a sectional view on line 2—2 of Fig. 1;

Fig. 3 is a sectional view taken on line 3—3 60 of Fig. 2, looking in the direction of the arrows;

Fig. 4 is a sectional view taken on line 4—4 of Fig. 2, looking in the direction of the 65 arrows;

Fig. 5 shows a sectional view partly broken away of the parts of a modified uncoupling device;

Fig. 6 is an end view taken on the line 6—6 of Fig. 5, looking in the direction of 70 the arrows;

Fig. 7 is a sectional view taken on line 7—7 of Fig. 5, looking in the direction of the 75 arrows;

Fig. 8 is a sectional view partly broken away of said modification showing the parts 80 assembled;

Fig. 9 is a top plan view showing the connecting device as applied to a lever system and a coupler pin; 85

Fig. 10 is an elevational view of the construction shown in Fig. 9;

Fig. 11 is a perspective view of a tool used in disconnecting the members of the improved uncoupling devices; 85

Fig. 12 is an elevational view showing the coupler, coupler pin, lever system and connecting device;

Fig. 13 is a perspective view of the spring clip associated with the modified uncoupling 90 device.

Fig. 1 illustrates the method of connecting an uncoupling rod 3 and a coupler pin 4 by means of a flexible uncoupling device. The flexible uncoupling device is shown supported from the uncoupling rod 3 by an open eye pigtail hook 1 while at the other end of the device is shown a portion of the coupler pin 4 attached to the device by means of a similar open eye pigtail hook 5. The hooks are constructed so that lines connecting similar points on the two hooks would lie in parallel planes and are connected together, as illustrated in Figures 2, 5 and 8 in a man-

ner such that they could not possibly acquire any other position relative to each other. A pair of holes 6, 6 are provided to allow the introduction of a special plier-like tool. 5 These holes are diametrically opposite each other as shown in Fig. 3.

As shown in Fig. 2, one pigtail hook 1 is made integral with a socket 8 and the other pigtail hook 5 is prolonged to form a 10 straight projection or shank 10 and is provided to be introduced into the socket 8. Two springs 11, 11 are riveted, one on each side, to the projection 10, by the rivet 12 and recline in recesses 36, 36 each of a depth 15 equal to or greater than the thickness of the corresponding spring. Thus the bolted ends of the spring 11, 11 are made flush with the sides of the projection 10 and the free ends of the springs 11, 11 are bent so as to project 20 from the side of the neck or shank, as shown in Fig. 2. The holes 6, 6 located slightly above the shoulders 14, 14 and diametrically opposite each other are provided to allow the two parts of the uncoupling device 25 to be separated from each other, thus enabling a rapid and simple means of disconnecting the coupler pin 4 or the uncoupling bar 3 from the pigtail hooks 5 and 1 respectively. This is accomplished by forcing the free ends of the springs 11, 11 into their corresponding recesses 36, 36 and thus allowing the springs to pass the shoulders 30 14, 14. When the uncoupling device is under tension, the free ends of the springs 11, 11 rest on the shoulders 14, 14 which prevent the neck or shank 10 from separating 35 from the socket 8. It should be noted that the thrusts on the springs 11, 11 by the shoulders 14, 14 are resisted not only by the rivet 12 but also by the shoulders 43, 43 at the upper ends of the recesses 36, 36.

Fig. 3 shows a sectional view of the socket 8 surrounding the neck or shank 10 and shows in dotted lines a portion of the tool 45 17 entering through the holes 6, 6 used for disconnecting the uncoupling device. The semi-circular slots 18, 18 are provided in the shoulders 14, 14, respectively, to permit the enlarged heads of the rivet 12 to pass by the shoulders 14, 14 when the releasing tool is applied to the springs 11, 11. The slots 24, 50 24 are provided to reduce the amount of metal required for construction of the socket member of the uncoupling device.

Fig. 4 shows an end view of the socket 8 and a sectional view of the neck 10 which is 55 slideable into the socket 8. Fig. 4 also shows the slots 18, 18 which allow the enlarged ends of the rivet 12 to pass by the shoulders 14, 14 and out of the socket 8. This arrangement insures that the members will be assembled correctly, thus tending to make the mechanism fool-proof. The enlarged projecting rivet heads and the slots 18, 18 compel the insertion of the neck or shank 10 so

that the springs 11, 11 will be in proper relation to the abutment 14, 14.

It is seen that the invention provides a separable uncoupling device that permits the attachment of one pigtail hook 1 of Fig. 1 to the uncoupling rod 3 and of another pigtail hook 5 to the coupler pin 4 before assembling the two members of the uncoupling device. Thus it is possible to employ long extended pigtail hooks 10 of a spiral nature to an uncoupling device and to attach the same to the coupler pin 4 and to the uncoupling rod or lever 3 without necessitating the removal of any parts of the rod or coupler. From the construction of the device shown in Figs. 3 and 4, it is obvious that the neck or shank 10 is restricted from rotation relatively to the socket 8 and thus the possibility of an accidental disconnection of the hook from the pin 4 or rod 3 is eliminated. Although the shank 10 can not rotate with respect to the socket 8, it is adapted to a limited telescopic longitudinal movement. This extensible feature is clearly illustrated by Fig. 2, showing the neck or shank 10 abutting against the end of the socket 8 with the hook 1 in its closest possible position to the hook 5. From this position the hooks are free to extend apart until the springs 11, 11 abut against the shoulders 14, 14 respectively.

Hence, a coupling device comprising members capable of being independently attached to the pin and rod respectively, equipped with attachment means incapable of being disconnected while in operation and adapted to a limited longitudinal extensibility, has been provided by the invention.

Figures 5, 6, 7, 8 and 13 show a modification of the uncoupling device. The shank or neck 25 of the pigtail hook 26 is beveled on two opposite sides 44, 44 to form an inverted V shaped end or head 48 and is provided with lateral recesses 27—27, one below each of the beveled sides respectively. The socket 37 is made integral with the pigtail hook 29 and is cored internally to form a housing 30 V shaped adjacent the hook end of the socket 37. The housing 30 bulges outwardly near the center of the socket 37 but is contracted at its lower portion, being bounded by inner sides or walls parallel to the external surface of the same near its open end. Shoulders 31, 31 are provided to restrict the opening of the housing 30 and to form abutments to prevent removal of the spring 32. This spring is preferably of the shape shown in Fig. 13, having flat sides 45, 45 arranged to tightly fit the V shaped end of the neck or shank 25 and also parallel flat sides 46, 46 fitting the inner parallel walls 47, 47 of the socket. This spring is equipped with flanges 28—28 perpendicular to the sides 46, 46 which are adapted to recline in the recesses 27, 27 of the neck 25.

Fig. 5 shows the neck 25 about to enter the housing 30 through the opening 36 at the end of the socket 37, while Fig. 8 shows the neck 25 in the housing 30 with the spring 5 clip 32 tightly clamped over it. When the neck 25 is introduced, the V-shaped end enters the small opening 36 of the clip 32 and causes the same to move into the enlarged belly of the socket 37. In this position the opening 36 of the spring clip 32 is free to expand and allow the shank 25 to enter its cavity and the flanges 28, 28 snap in the recesses 27, 27. Thus it is seen that once the head of the neck 25 is so jacketed that it cannot 10 become detached from the socket 37 it will have a limited freedom of motion in the direction of the length of the uncoupling device 34, thereby making the connection between the hooks 26 and 29 limitedly extensible.

It is seen in Fig. 6 that the entrance to the housing of the socket 37 is rectangular in shape and that a shank or neck of rectangular cross-section could not rotate within said housing. Thus the hook 29 of the socket 37 cannot rotate relatively to the hook 26 of the shank 25 and for this reason the spiral hooks cannot be detached by jar or vibration from their respective holdings 25 and cannot get in a position where they will kink or bind in the eyes 52 and 53 or either of them.

The invention provides a limited longitudinally extensible uncoupling device comprising members restricted from rotation relatively to each other and capable of being assembled after attachment. The latter feature makes possible the employment of extended spiral pigtail hooks that may be 35 inserted in openings, spiraled into a vertical position and then connected together. Thus a secure attachment is obtained without necessitating the removal of any parts of the coupler pin or the uncoupling rod.

Figs. 9, 10 and 12 show the uncoupling device 34 in its intended position connecting the coupler pin 4 to the uncoupling bar or rod 33 by means of which the pin 4 may be lifted or lowered from the side of the car.

Fig. 11 shows the type of tool adapted for use in disconnecting the uncoupling device. This tool comprises two members 40, 40 pivoted in pincher-like fashion at 41 and bent so as to produce a compressive force at their 50 jaw ends 39, 39 when the handles 42, 42 are pressed together.

The bar 33 of Fig. 10 is shown connected to the pin 4 by the connecting device 34 and in Fig. 12 the connecting device 34 is shown 60 in its various positions by dotted lines 50, 50 illustrating the degree of lateral flexibility provided for the device to permit relative movement of cars or the means for securing uncoupling. In Fig. 10 the uncoupling bar 33 is provided with an arm or lever 3 and an

eye 52 through which the pigtail hook 1 is spiraled and the pin 4 is provided with an eye 53 through which the hook 5 is spiraled. The hooks 5 and 1 are by means described 70 capable of being connected after attachment to the pin 4 and to the rod 33 respectively so as to provide a separable limitedly extensible uncoupling device adapted to compensate for vibration and for end play in the coupler. Thus it is seen that extended spiral pigtail 75 hooks 1 and 5 may be employed and attached to or spiraled through the eyes 52 and 53 respectively before the uncoupling device is assembled.

Obviously those skilled in the art may 80 make various changes in the details and arrangements of the parts without departing from the spirit and scope of the invention defined by the claims hereto appended, and it is therefore desired not to restrict 85 to the precise construction herein disclosed.

Having thus fully described and shown an embodiment of the invention, what is desired to be secured by Letters Patent of the United States is:

I claim:

1. In mechanism for coupling and uncoupling cars, the combination with a locking and unlocking device, of separable means adapted to connect said unlocking and locking device to operating mechanism, a flexible abutting means on parts of said separable means provided to restrict motion and to prevent separation of said separable means, rigid abutting means on parts of said separable means, and clamping means provided to make a portion of said flexible abutting means fast to said separable means.

2. In mechanism for coupling and uncoupling cars, the combination with a locking and unlocking device, of separable means adapted to connect said locking and unlocking device to operating mechanism, rigid abutting means on parts of said separable means, flexible abutting means on parts of said separable means, and means of access to said flexible abutting means provided to permit manipulation of said flexible abutting means.

3. A combination with a coupler, of a locking pin, an unlocking lever and means connecting said pin and lever comprising a pair of members provided with hooks engaging said lever and pin and means connecting said members together detachably comprising means on said members automatically interengaging upon axial movement of said members toward each other.

4. The combination with a coupler, of a locking pin, an unlocking lever and means connecting said pin and lever comprising a pair of members, one of said members being provided with a housing and the other of said members having means entering said housing, one of said members being pro-

- vided with an abutment and flexible means on the other of said members co-operating with said abutment to hold said members from separation.
5. The combination with a coupler, of a locking pin, an unlocking lever and means connecting said pin and lever comprising a pair of members, one of said members being provided with a housing and the other of 10 said members having means entering said housing, one of said members being provided with an abutment and flexible means on the other of said members normally co-operating with said abutment to hold said 15 members from separation, said flexible means being adjustable to permit separation of said members.
6. The combination with a coupler, of a locking pin, an unlocking lever and means connecting said pin and lever comprising a pair of members, one of said members being provided with a housing having a restricted entrance and the other of said members having means entering said housing, one of said 20 members being provided with an abutment and flexible means on the other of said members co-operating with said abutment to hold said members from separation, said flexible 25 means being distortable out of its normal means being distortable out of its normal position to pass through said entrance.
7. The combination with a coupler, of a locking pin, an unlocking lever and means connecting said pin and lever comprising a pair of members, one of said members being 30 provided with a housing having a restricted entrance and the other of said members having means entering said housing, one of said members being provided with an abutment and flexible means on the other of said members co-operating with said abutment to hold 35 said members from separation, said flexible means being distortable out of its normal position to pass through said entrance before engagement thereof with said other member.
45. 8. In mechanism for coupling and uncoupling cars, the combination with a locking and unlocking device, of means for operating the same, separable, convenient, connecting means provided to connect said unlocking and locking device to said operating means, rigid abutting means provided on said convenient connecting means, flexible abutting means provided on said abutting means, clamping means adapted to secure 50 said flexible abutting means fast to said convenient connecting means at one end and allow said flexible abutting means to protrude at the other end, a recess provided on said convenient connecting means adapted 55 to receive the protruding end of said flexible abutting means, and means of attachment made integral with said convenient connecting means adapted to connect said convenient connecting means to operating mecha- 60 nism and to said locking and unlocking device.
9. In an uncoupling and coupling device, the combination with spaced apart hooks, of a connection between the same, comprising means on one of said hooks engaging with means on the other of said hooks to normally prevent separation thereof, but movable to permit separation of one hook from another by movement axially of said connection, while made fast to their respective holdings, 70 said connection comprising extensible means adapted to permit a variation in the distance between said spaced apart hooks.
10. The combination with a coupler, of a locking pin, an unlocking lever and means connecting said pin and lever comprising a pair of members provided with hooks engaging said lever and pin and means connecting said members by axial movement thereof toward each other after engagement 75 with said lever and pin.
11. The combination with a coupler, of a locking pin, an unlocking lever and means connecting said pin and lever comprising a pair of members provided with hooks 80 engaging said lever and pin and means connecting said members by movement thereof toward each other in substantially a straight line after engagement with said lever and pin.
12. The combination with a coupler, of a locking pin, an unlocking lever and means connecting said pin and lever comprising a pair of members having means thereon automatically interlocking to connect the same 85 upon axial movement of said members into engagement with each other, said means comprising a fixed abutment on one of said members and movable means on the other of said members normally engaging said abutment.
13. The combination with an uncoupling lever and a coupler lock, of extensible and contractible means connecting said lever and lock comprising a pair of separable members and abutments on said members to limit the relative movement of said members in both directions, certain of said abutments being movable out of normal position relative to the member upon which they are mounted 95 to permit separation of said members.
14. The combination with a coupler, of a locking pin, an unlocking lever and means connecting said pin and lever comprising a pair of members having means thereon interlocking to connect the same, comprising means movably mounted on one of said members normally engaging fixed means on the other of said members but movable out of such position to avoid said fixed means and permit separation of said members.
15. Uncoupling mechanism comprising separate hooks, one adapted to be connected

- to operating mechanism on a car and the other to coupler mechanism, and interlocking devices one on one hook and the other on the other hook, said interlocking devices 5 being adapted to be interlocked by relative axial movement of said devices after said hooks are respectively connected to said operating mechanism and to said coupler mechanism.
- 10 16. Uncoupling mechanism comprising two separate and independent attaching means, one adapted to be connected to operating mechanism on a car and the other to coupler mechanism thereon, and interlocking 15 mechanism comprising separate elements, one connected to one of said attaching means and the other to the other attaching means, said separate elements being adapted to be connected by relative axial movement of 20 said devices and without rotation thereof to complete the interlocking operation after said attaching means have been connected to the operating mechanism and to the coupler mechanism.
17. Uncoupling mechanism comprising 25 a member having a pigtail hook spiraled 360° or more and adapted to be connected to operating mechanism on a car, a member having a pigtail hook also spiraled 360° or more and adapted to be connected to 30 coupler mechanism on the car, and means on said members for connecting the same after being connected respectively to said operating mechanism and coupler mechanism without removal thereof from the car. 35

In testimony whereof I have signed my name to this specification on this 29th day of March, A. D. 1924.

ARTHUR F. O'CONNOR.
